US00D971884S

(12) **United States Design Patent** (10) **Patent No.:** **US D971,884 S**
(45) **Date of Patent:** **** Dec. 6, 2022**

(54) **CONTROLLER**

(71) Applicant: **Bio-Medical Research Limited**,
Galway (IE)

(72) Inventor: **Conor Minogue**, Galway (IE)

(73) Assignee: **Bio-Medical Research Limited**,
Galway (IE)

(**) Term: **15 Years**

(21) Appl. No.: **29/752,835**

(22) Filed: **Sep. 29, 2020**

(51) LOC (13) Cl. **14-03**

(52) U.S. Cl.

USPC **D14/218**

(58) **Field of Classification Search**

(57) **CLAIM**

The ornamental design for a controller, as shown and described.

DESCRIPTION

FIG. 1 is a top, front perspective view of a controller showing my new design;

FIG. 2 is a top view thereof;

FIG. 3 is a bottom view thereof;

FIG. 4 is a left side view thereof;

FIG. 5 is a right side view thereof;

FIG. 6 is a rear view thereof; and,

FIG. 7 is a front view thereof.

The broken lines depicting the remainder of the controller form no part of the claimed design.

1 Claim, 7 Drawing Sheets
